PIPE CONSTRUCTION

David Homer Hayden, New York, N. Y.

Application August 13, 1932. Serial No. 628,690

9 Claims. (Cl. 131—12)

My invention relates to pipes particularly intended for smoking tobacco.

One object is to provide a pipe which will remove from the smoke most of the surplus moisture and other condensable products of combustion.

Another object is to provide a construction which will collect the solid residue without clogging up the smoke passage.

10. Another object is to provide a construction which will to a large extent remove the nicotine, coal tar and similar products of the combustion.

Another object is to provide a construction which will smoke cool.

15. Another object is to provide a construction which will produce a uniform flavor throughout the entire smoke.

Another object is to provide a construction which while it takes up the surplus moisture 20 when the pipe is first lighted will add moisture toward the end of the smoke, thus giving an equalized sensation and flavor during the entire period of smoking.

Another object is to provide a construction 25 having an absorbent member which can be readily removed and replaced.

Another object is to provide a construction of the character described which is light in weight and which can be made in attractive forms.

30. Another object is to provide a pipe which can be successfully made very light and yet uniform and durable.

A special object is to provide a pipe, the outer and inner parts of which can be made of molded 35 composition such as thermoplastic phenolic condensation products.

In carrying out the invention I preferably form the pipe in three parts, namely, (1) an outer body portion to which the stem is attached 40 either integrally or otherwise, (2) an inner bowl for receiving the tobacco and forming the combustion chamber, and (3) an intermediate absorbent sleeve or cup-like body which fits into the outer main body and itself receives the combustion receptacle or lining.

The invention may be embodied in a number 45 of different modifications, some of which are shown and described hereinafter.

Fig. 1 is a cross sectional view of one form of 50 construction.

Fig. 2 is a side view of the absorbent member of Fig. 1.

Fig. 3 is a vertical sectional view of a modification.

55. Fig. 4 is a sectional view showing an additional

protective cup which may be employed in some cases.

Fig. 5 is a sectional view of another modification.

The main body 10 may be formed of any suitable material such as briarwood or molded composition in any suitable design, size or shape. 60

The receptacle 11, which is intended to hold the tobacco, may be formed of suitable material such as molded fireclay, bakelite or other molded 65 composition.

The intermediate body 12 is preferably formed of a highly absorbent material such as balsawood. Externally the dimension is such that it will fit snugly within a recess in the main body, 70 and internally it is made to receive the bowl 11 which fits snugly at the top but leaves a substantial chamber 13 in the bottom and around the sides of the bowl.

The tobacco bowl 11 is provided with one or 75 more outlets 14 in or near the bottom which open into the chamber 13. The exterior of the intermediate body is provided with a groove 15 which is continuous from the upper portion to the lower portion and may be cut helically with its 80 upper end communicating through a passage 16 with the upper part of the chamber 13 and with its lower part communicating with the entrance 17 to the stem, thus forming a smoke passage from the combustion chamber of the bowl 11 so 85 that the smoke passes through the outlet 14 into the chamber 13, rises around the sides of the combustion bowl, passes through the opening 16 into the groove 15, thence traveling round and round the absorbent body 12 and out through the exit 90 17 to the stem.

When material such as balsawood is employed it is desirable to protect this material from sparks and direct flame through the opening 14, for instance, by means of an incombustible disc 18. 95 This disc may be of any suitable fire-resisting material such as fireclay or a metal in the form of a tack which can be readily inserted into the bottom of the absorbent member 12.

In order that the groove 15 shall prove effective 100 as a continuous channel it is, of course, desirable that the outer wall of the body 12 fit snugly in the main body at the top and bottom and between the convolutions of the groove.

For this reason the intermediate body 12 is 105 made large enough to fit snugly within the cavity in the body 10 and as an additional precaution the upper edge 19 and the lower edge 20 may be originally cut somewhat larger in diameter than the corresponding interior diameters of the body 110

so that when the intermediate member 12 is inserted it is forced into place and the edges 19 and 20 are compressed by reason of the resilient character of the material of which it is made. The compression at the top also tightly grips the exterior of the combustion member 11 so as to hold it tightly in place when the parts are assembled. Tight joints are very desirable throughout the entire structure in order to insure an efficient draught. The slightly cup-shaped disc 18 corresponds with the incombustible disc 18 of Fig. 1 and may be of similar material for protecting the balsawood against ignition.

Preferably the main body and the intermediate body are so constructed as to facilitate assembly and separation and for this purpose the bottom of the main body 10 is provided with an opening 21 and the intermediate body 12 is provided with a stem or projection 22 which fits into the opening 21. When it is desired to remove the intermediate member it is thus merely necessary to press upwardly on the stem 22 or vice versa downwardly on the body while the stem is supported.

When in operation the smoke passes from the combustion chamber into the chamber 13 where some of the moisture is first absorbed. As the smoke passes outwardly through the opening 16 into the helical groove and around the intermediate member 12 more of the moisture together with other volatile products are absorbed in the exterior walls of the absorbent body 12. This body 12 also acts as a thermal insulator so that a great deal of the heat of combustion is prevented from reaching the bowl 10. The pipe therefore never gets so hot as to be uncomfortable to the hand. Some thermal insulation is also afforded by the air space in the upper part of the chamber 13 around the sides of the combustion chamber. When the combustion chamber gets hot it also serves to evaporate the moisture from the inner wall of the absorbent member 12 so that moisture is restored to the smoke as the operation goes on. The chamber 13 also provides a space for the collection of ash and condensation of the heavier volatile residues.

In such a construction it is possible to burn up all of the tobacco in smoking in the usual way because there is no collection of moisture in the bottom of the combustion bowl to interfere with complete combustion.

During the entire period of combustion the temperature maintained in chamber 13 is sufficient to prevent the volatile gases from condensing, thus separating the gases from the heavy residues.

In the form of construction shown in Fig. 3 the intermediate member 12' is provided with circular channels 15' connected by vertical channels 15" so as to provide in effect a continuous channel from top to bottom although not mathematically a helical channel. In this case the bottom 22' of the absorbent member is substantially the full diameter of the member instead of being reduced in size as shown in Figs. 1 and 2. The latter construction is suitable for many designs but is more limited in its application than the type of construction shown in Figs. 1 and 2.

When the intermediate body is formed of material which is highly absorbent like balsawood it is desirable to coat or otherwise protect the upper and lower ends with a waterproof composition or material such as shellac so as to seal the ends.

Preferably the body 12 is turned up from balsawood with the grain running parallel to the axis of the pipe bowl, thus affording maximum mechanical strength and at the same time in the

exterior grooves exposing the most absorbent cellular structure of the wood.

In place of the member 18 for protecting the member 12 from combustion I may employ a metal cup 23 which is adapted to be inserted into the lower end of the cavity of the member 12 and is retained frictionally or by means of tangs 24 formed by punching holes in the member 23 and pressing the cut metal outwardly so that it will interlock with the absorbent body.

The form of construction shown in Fig. 5 is especially adapted to be made of molded composition in which the main body 25 extends only a part of the height of the bowl and the remainder of the exterior of the bowl is formed by a flange 26 which is integral with the combustion receptacle 27. In this case the absorbent sleeve 28 is inserted in the member 25 and compressed at the top by the combustion receptacle. A fire-resistant member 30 is corrugated at 31 and formed with a helical groove 31 in its exterior and fits snugly within the absorbent sleeve 28. The combustion chamber 27 has the usual exit 32 at the bottom and fits snugly against the upper end 33 of the grooved member 30. There is a passage 34 through the wall of the member 30 communicating with the groove 31 and the lower end of the groove 31 communicates with the space 35 which is in communication with the exit 36 to the stem. In this case the ash chamber 37 is formed in the non-absorbent member 30. This construction is particularly adapted to fabrication from molded materials which can be made thin and therefore very small in size. This, of course, can be made in any size and provides a maximum tobacco cavity for a given size of pipe.

It should be understood that the long channel around the member 12 might be cut as a helical groove in the inner wall of the body 10, in which case the body 12 would be smooth on the exterior but still absorbent.

It is preferable, however, that the groove should be cut in the absorbent member because in this way a greater absorbent area is provided.

Another advantage is that in the construction shown in Fig. 1 the interior of the main body is perfectly smooth and can therefore be readily cleaned, it being understood, of course, that the intermediate member 12 when saturated will be thrown away. It will be understood, of course, that the inner tobacco compartment may also be renewed from time to time.

While the intermediate absorbent member has been described as preferably of balsawood, certain advantages of the invention may accrue from the use of other materials such, for instance, as corn cob, and I therefore wish it understood that the claims are to be construed broadly within their respective terms although balsawood has great advantages specifically for many purposes.

I claim:

1. A pipe having an outer bowl with a passage through the bottom and a stem at one side, an absorbent body inserted into the bowl from the top and removable by pressure through the bottom passage, a combustion receptacle secured in the absorbent body and having an outlet at the bottom, said absorbent body forming an ash and smoke receiving chamber beneath and around the receptacle, the bowl and body having between them a circuitous groove connected at one end to said chamber and at its other end with said stem.

2. A pipe member formed of absorbent balsa-

wood with compressible flanges at the top and bottom to fit in a pipe bowl and means for protecting the member from being ignited by means in the pipe bowl.

5 3. A pipe member formed of highly absorbent material having external encircling grooves and compressible flanges at the top and bottom.

4. A pipe member formed of absorbent and resilient material having an external encircling 10 groove and a compressible flange at the bottom.

5. A pipe having an outer bowl with an open mouth at the top and a passage through the bottom and a stem at one side, an absorbent body inserted into the open mouth of the bowl

15 and removable by pressure through the bottom passage, and a combustion receptacle secured in the absorbent body and having an outlet at the bottom, said absorbent body having an ash and smoke receiving chamber with a fire-proof

20 insert beneath the receptacle, the bowl and body having between them a groove connected at one end to said chamber and at its other end with said stem.

6. A pipe construction comprising a main body 25 member with stem connection, a combustion receptacle, a flanged member connecting the combustion receptacle and pipe body, a casing of fire-resisting material having an ash receiving chamber and a removable resilient and absorbent 30 body of balsawood which fits snugly in the main body and also engages the walls of said casing so as to form a smoke passage.

7. A pipe construction comprising a bowl hav-

ing a stem, a combustion receptacle having an outer downwardly depending body flange meeting the upper edge of the bowl, a resilient highly absorbent sleeve of balsawood clamped between the bowl and the upper part of the combustion receptacle and a fireproof lining interposed between said sleeve and said receptacle and having a circuitous groove formed in its outer wall forming in connection with the sleeve an absorbent channel, said receptacle having an opening in its lower part communicating with said lining.

8. A pipe having a bowl member open at the top and having an opening in the bottom in line with the top opening, an absorbent cup-like member inserted into the bowl through the top opening and removable from the bowl by pressure applied through the bottom opening, and a fire-proof lining member forming a combustion chamber, said lining member being inserted into the absorbent member, said members having smoke passages between the lining member and the absorbent member and between the absorbent member and the bowl member.

9. A pipe construction comprising an outer 100 body, an inner combustion receptacle, an intermediate highly absorbent body of balsawood, and fireproof means for protecting the balsawood against ignition from above the bottom of the combustion receptacle, said fireproof means being 105 situated between the inner combustion receptacle and the balsawood.
